UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,271,632.

Specification of Letters Patent.

Patented July 9, 1918.

Application filed April 14, 1917. Serial No. 162,000.

To all whom it may concern:

Be it known that I, HENRY G. VOIGHT, a citizen of the United States, residing in New Britain, county of Hartford, State of Connecticut, have invented certain new and useful Improvements in Locks, of which the following is a full, clear, and exact description.

This invention relates to locks, and it has special reference to corridor door locks of hotels. The invention also relates particularly to mortise locks of the type in which a dead bolt is protractable from the outside of the room by a cylinder lock mechanism, and is protractable from the inside of the room by a thumb turn or the like.

One of the primary objects of the invention is to furnish a very simple, inexpensive and efficient tumbler mechanism for a lock of the general character stated.

Another object of the invention is to provide an improved form of lock in which a change key when inserted from the outside and turned will retract a latch bolt without, however, having any effect on the dead bolt, and wherein the emergency key, on the other hand, will operate the dead bolt as well as the latch bolt.

Another object of the invention is to provide very simple, effective means for operating a dead bolt by means of a thumb turn hub.

To these and other ends, the invention consists in the novel features and combination of parts to be hereinafter described and claimed.

In the accompanying drawings,

Figure 1 is an elevation of the lock embodying my improvements, with the cap plate removed, showing the dead bolt in the normal retracted position;

Fig. 2 is a view of the upper part of the lock, showing the latch retracted by the change key;

Fig. 3 is a section on line 3—3 of Fig. 1;

Fig. 4 is an elevation, showing the dead bolt partly protracted by the emergency key;

Fig. 5 is a section on line 5—5 of Fig. 4;

Fig. 6 is a view similar to Fig. 4, showing the dead bolt fully protracted;

Fig. 7 is a section on line 7—7 of Fig. 6, showing the change key inserted into the cylinder;

Fig. 8 is a view similar to Fig. 7, showing the emergency key inserted into the cylinder;

Fig. 9 is a detail of the dead bolt;

Fig. 10 is a detail rear view of the tumbler connector.

In the drawings, I have shown my improvements applied to a lock having the usual mortise case, with a face plate 21. In the upper part of the lock a dead bolt 22 is located, and in the lower part is a latch bolt 23. The latch bolt mechanism forms no part of the present invention, but it may be stated that said bolt is retractable from the inside by the usual knob spindle, acting on a hub 24 to draw back a retracting shoe or yoke 25, and in the particular case illustrated the outside knob, which is connected by its spindle to a hub member 26 is permanently dogged by a portion 26^a on said hub member extending between lugs 27 on the case. The knob shoe 25 has a shoulder 75 located in front of a cross-head 28 on the rear end of the latch bolt stem 29, which stem is surrounded by the usual spring 30.

In the upper part of the lock, a cylinder 31 is screwed in at the outer side, and this cylinder, through connections to be herein-after described, is adapted to actuate a latch-retracting lever 32, pivoted in the upper part of the case at 33 and having its lower extremity in front of the cross-head 28. The dead bolt 22 has a flat shank 35, with talons 36 adjacent the cylinder lock 31, and a cut out portion 37 in the upper part of the shank receives the fence or stump 38 cast on the back of the case. This fence guides the bolt for reciprocating movement, and it is also guided in a suitable manner at the lower part of the bolt shank. Below the talons, the bolt has a cut out portion 39 to receive a thumb turn hub 40, which is journaled between the back and cap plate of the case. In the lower part of the cut-out or aperture 39 a gate 41 is formed to co-operate with a wing 42 on the thumb turn hub. This gate 41 is provided with beveled or inclined surfaces to co-operate in an obvious manner with the extreme edge of the wing 42 to dead lock the bolt in protracted position and retracted position respectively, and between the beveled or inclined surfaces a small notch is provided to receive

the bolt for reciprocating movement, and it is also guided in a suitable manner at the lower part of the bolt shank. Below the talons, the bolt has a cut out portion 39 to receive a thumb turn hub 40, which is journaled between the back and cap plate of the case. In the lower part of the cut-out or aperture 39 a gate 41 is formed to co-operate with a wing 42 on the thumb turn hub. This gate 41 is provided with beveled or inclined surfaces to co-operate in an obvious manner with the extreme edge of the wing 42 to dead lock the bolt in protracted position and retracted position respectively, and between the beveled or inclined surfaces a small notch is provided to receive

the bolt for reciprocating movement, and it is also guided in a suitable manner at the lower part of the bolt shank. Below the talons, the bolt has a cut out portion 39 to receive a thumb turn hub 40, which is journaled between the back and cap plate of the case. In the lower part of the cut-out or aperture 39 a gate 41 is formed to co-operate with a wing 42 on the thumb turn hub. This gate 41 is provided with beveled or inclined surfaces to co-operate in an obvious manner with the extreme edge of the wing 42 to dead lock the bolt in protracted position and retracted position respectively, and between the beveled or inclined surfaces a small notch is provided to receive

the bolt for reciprocating movement, and it is also guided in a suitable manner at the lower part of the bolt shank. Below the talons, the bolt has a cut out portion 39 to receive a thumb turn hub 40, which is journaled between the back and cap plate of the case. In the lower part of the cut-out or aperture 39 a gate 41 is formed to co-operate with a wing 42 on the thumb turn hub. This gate 41 is provided with beveled or inclined surfaces to co-operate in an obvious manner with the extreme edge of the wing 42 to dead lock the bolt in protracted position and retracted position respectively, and between the beveled or inclined surfaces a small notch is provided to receive

the bolt for reciprocating movement, and it is also guided in a suitable manner at the lower part of the bolt shank. Below the talons, the bolt has a cut out portion 39 to receive a thumb turn hub 40, which is journaled between the back and cap plate of the case. In the lower part of the cut-out or aperture 39 a gate 41 is formed to co-operate with a wing 42 on the thumb turn hub. This gate 41 is provided with beveled or inclined surfaces to co-operate in an obvious manner with the extreme edge of the wing 42 to dead lock the bolt in protracted position and retracted position respectively, and between the beveled or inclined surfaces a small notch is provided to receive

the edge of the wing as the latter is moved through a quarter turn for protracting or retracting the bolt.

The bolt is provided with a tumbler 43, pivoted on a post 44 at the forward part of the bolt shank, so as to be carried by the bolt, and having a projection 45 extending between the talons 36 into coöperation with the cylinder lock, as hereinafter described.

10 This tumbler 43 is provided intermediate its ends with a lug 46 to coöperate with the fence 38 in locking the bolt either in the retracted position or the advanced position. Below the tumbler 43 and pivoted to the lock case is a second tumbler 47 which coöperates with the thumb turn hub in dead-locking the dead bolt. This tumbler is pivoted on a post 48, and has a spring 49 reacting against a lug 50. The main part 15 of tumbler 47 overlies the lower portion of the dead bolt shank, and at its upper part the tumbler is provided with notches which converge toward the upper edge of the tumbler and meet each other near the upper edge of the tumbler. One of these notches is indicated at 51 and the other at 52, and the spring exerts an upward thrust on the tumbler so as to tend to keep it firmly seated against the thumb turn hub with one or 20 the other of the notches 51, 52 engaging the wing 42. The tumbler by being provided with these notches exerts such an upward thrust on the wing 42 as to hold it in coöperation with one or the other of the inclined surfaces of the gate 41, so that the bolt will be securely deadlocked either in the retracted position or the protracted position, and cannot be moved out of this position except by actuation of the thumb turn 25 or the key mechanism. As the bolt is moved to and fro by turning the hub 40, the part of the tumbler 47 adjacent the notches quickly snaps against the under surface of the wing and presses and holds it against the coöperating inclined surfaces of the bolt gate.

The spring action of the lower tumbler is imparted to the upper tumbler by means of a tumbler connector 53, which may take the form of a small plate. In the example shown, this plate has upper and lower pins 54, 55 projecting rearwardly therefrom; the pin 54 entering a slot 56 in the upper tumbler, and the lower pin 55 entering a small hole in the lower tumbler. The slot 56 permits the bolt to be shifted without disturbing the connection of the upper movable tumbler with the fixed lower tumbler, as will be understood. The upper part of the connecting plate is also preferably notched, as shown at 57, to fit around the fence 38. This guides the tumbler connector in its vertical movement as the tumblers are depressed and maintains the upper part of the connector in the proper relation to the slot 56.

The cylinder lock 31 is preferably of the kind shown in my application Serial No. 95376, and as shown in Figs. 7 and 8, it has the usual case 58 in which is rotatable a key plug 59 controlled by sectional pin tumblers 60. Around the rear end of the key plug, is a short sleeve 61, and the rearmost pin tumbler 60^a coöperates with this sleeve and with the casing in such a manner that when it is in one position it locks the sleeve to the casing and releases the key plug, while in another position it locks the key plug to the sleeve and releases it from the casing. On the rear end of the key plug is a roll-back or cam 62, and on the rear end of the sleeve is a cam or rollback 63. These cams or rollbacks are disposed in parallel planes, being spaced from each other by a washer 64, the key-plug-rollback being at the rear of the sleeve-rollback.

The latch-retracting lever 32 previously described may be actuated from the cylinder lock by means of a lever 65, pivoted on the dead bolt and carried thereby. This lever is pivoted on the dead bolt shank at 67 and its free end is adapted to extend into coöperation with the upper edge of the lever 32 when the dead bolt is in the retracted position, so that by depressing the lever 65 the lever 32 may be actuated to retract the latch. For this purpose, the lever 65 is provided intermediate of its ends and in proximity to the cylinder lock with a comparatively deep operating projection 68 close to and having portions in substantial alignment with both cams or rollbacks 62, 63, so that said lever may be actuated by the rotation of either rollback. It will be observed, however, that the operating projection 45 on the upper tumbler while disposed in the plane of the auxiliary or sleeve cam 63 is not located in the plane of the key-plug-rollback or cam 62, so that the latter will not actuate said tumbler.

The operation of the improved lock is substantially as follows: Fig. 1 shows the parts in the normal position. When the guest enters the room and desires to lock the door from the inside, the thumb turn is actuated, as previously described, to advance the dead bolt. To permit this operation, the upper tumbler must, of course, be released and this is effected by the tumbler connector 53, which is pulled down by the lower tumbler and depresses the upper tumbler by means of the pin 54 engaging the lower edge of the slot 56. When the dead bolt is protracted, it is impossible to actuate the latch from the outside by means of a change key 65 nor other key of low order, owing to the fact that the regular cam 62 which is operated individually by such key, cannot reach the lever 65, which is shifted toward the face plate of the lock into any inoperative position over the fence 38. The

keys of lower order will not, of course, operate the dead bolt as the cam 62 rotates clear of the tumbler 43 and the dead bolt talons. The lock can, however, be released by the 5 emergency key 66, which is somewhat longer than the change key, and is bitted to engage and actuate the rearmost pin tumbler 60^a to lock the sleeve to the key plug and release it from the casing. On turning the 10 emergency key in the lock the dead bolt can be retracted by the cam 63 in an obvious manner. During this operation, the lower tumbler coöperating with the thumb turn member is released from its locking position 15 by the tumbler connector 53 which depresses said tumbler and permits the wing on the thumb turn hub to be shifted from the notch 52 to the notch 51.

My improved lock, as herein described, 20 is very simple, compact and inexpensive, and is reliable and secure. The parts are comparatively few in number, can be readily made, and are not liable to get out of order.

Various changes may be made in the 25 details of the construction without departing from the scope of the invention as defined in the claims.

What I claim is:

1. In a lock, a case, a dead bolt therein, 30 a tumbler for said bolt carried thereby, a tumbler mounted on the case, operating means coöperating with the first tumbler, and another operating means coöperating with the second tumbler.

35 2. In a lock, a case, a dead bolt therein, a tumbler carried by the bolt, another tumbler pivoted to the case, operating means coöperating with the first tumbler, another operating means coöperating with the second tumbler, and means for operating said tumblers concurrently.

40 3. In a lock, a case, a dead bolt therein, a tumbler for said bolt pivoted thereon a second tumbler for said bolt pivoted to the case, means for interconnecting said tumblers, and means for operating said tumblers.

45 4. In a lock, a case, a dead bolt therein, a tumbler pivoted on said bolt, a fence coöperating with said tumbler, means for actuating said tumbler, and a second tumbler pivoted to the case and connected with the first tumbler.

50 5. In a lock, a case, a dead bolt therein, a tumbler for said bolt carried thereby, a second tumbler for said bolt pivoted to the case, key mechanism for operating one of said tumblers and protracting and retracting the bolt, and a thumb turn member for operating the other tumbler and protracting and retracting the bolt.

55 6. In a lock, a case, a dead bolt therein, a tumbler for said bolt carried thereby, a second tumbler for said bolt pivoted to the case, a thumb turn hub coöperating with

said second tumbler, and a cylinder lock mechanism coöperating with the first tumbler.

70 7. In a lock, a case, a dead bolt therein, a tumbler for said dead bolt carried thereby, a cylinder lock coöperating with said tumbler to protract and retract the bolt, a second tumbler pivoted to the case, means for connecting the second tumbler with the first, and a thumb turn hub for operating 75 the second tumbler and protracting and retracting the bolt.

80 8. In a lock, a dead bolt having a cut out portion with a gate therein, a hub operating in said cut out portion and having a wing coacting with said gate, and a tumbler having notches to engage the wing of 85 said hub.

85 9. In a lock, a bolt having a shank with a cut out portion therein and a gate in said cut out portion having inclined side walls, a thumb turn hub having a wing coacting with said inclined walls of the gate in dead-locking the bolt, and means for holding the edge of the wing in coöperation with said 90 inclined side walls.

95 10. In a lock, a bolt having a shank with a cut out portion therein, and a gate in said cut out portion having inclined side walls, a thumb turn hub having a wing coacting with said inclined walls of the gate in dead-locking the bolt, and means for holding the edge of the wing in coöperation with said inclined side walls, said means comprising a spring pressed tumbler having convergent 100 notches to receive the wing.

105 11. In a lock, a case, a dead bolt therein having talons at the upper part, a tumbler pivoted on said bolt and having an operating projection disposed between said talons, key mechanism coöperating with said projection and said talons, a fence coöperating with said tumbler, the lower part of the bolt shank having a cut away portion, a thumb turn hub operating in said cut away portion 110 to advance and retract the bolt, a tumbler pivoted to the case and coöperating with said thumb turn hub, and means for interconnecting said tumblers.

115 12. In a lock, a case, a dead bolt therein having talons at the upper part, a tumbler pivoted on said bolt and having an operating projection disposed between said talons, key mechanism coöperating with said projection and said talons, a fence coöperating 120 with said tumbler, the lower part of the bolt shank having a cut away portion, a thumb turn hub operating in said cut away portion to advance and retract the bolt, a tumbler pivoted to the case and coöperating with said thumb turn hub, and means for interconnecting said tumblers, comprising a plate pivotally connected with the second tumbler and having sliding connection with the first tumbler.

13. In a lock, a case, a dead bolt therein, a tumbler on said bolt, a tumbler on said case, key mechanism coöperating with one of said tumblers, thumb turn mechanism coöperating with the other tumbler, and means for operating said tumblers concurrently.

14. In a lock, a bolt, a tumbler carried thereby, a fence coöperating with said tumbler, operating means for said tumbler, a second tumbler for said bolt, and a thumb turn hub coöperating with said second tumbler to deadlock the bolt and adapted to protract and retract said bolt.

15. In a lock, a bolt, a tumbler carried thereby, a case inclosing said bolt and tumbler, a second tumbler for the bolt pivoted on the case, and a thumb turn hub coöperating with said second tumbler to deadlock the bolt and adapted to protract and retract said bolt.

16. In a lock, a case, a dead bolt therein, a tumbler for said bolt carried thereby, a second tumbler, a thumb turn hub coöperating with said second tumbler to deadlock the bolt and adapted to protract and retract the same, and means for operating said tumblers concurrently.

17. In a lock, a bolt, a tumbler, and a thumb turn hub having a wing coöperating

with said tumbler to deadlock the bolt, and adapted to protract and retract said bolt, said tumbler having notches formed therein to engage the wing of said hub.

18. In a lock, a bolt, a case, two tumblers for the bolt, one of said tumblers pivoted to the bolt and the other pivoted to the case, separate operators for the respective tumblers, and means of connection between said tumblers.

19. In a lock, a bolt having a gate with oppositely inclined surfaces, a hub having a radial wing for protracting and retracting the bolt and adapted to deadlock the same either in the protracted or the retracted position by engagement of said wing with one or the other of said inclined surfaces, and means having wing-receiving notches formed therein for holding the hub in one or the other of said positions.

20. In a lock, a case, a bolt therein, a tumbler pivoted on the bolt, a second tumbler pivoted on the case, separate actuators for said tumblers, and a tumbler connector having a fixed point of connection with the second tumbler and a sliding connection with the first tumbler.

In witness whereof I have hereunto set my hand on the 10th day of April, 1917.

HENRY G. VOIGHT.
